CARBURETOR

Jeptha Mackenzie Miller and Willard B. Goodman, South Bend, Ind., assignors to Bendix Aviation Corporation, South Bend, Ind., a corporation of Delaware

Application November 23, 1931
Serial No. 576,898

5 Claims. (Cl. 261—34)

This invention relates to carburetors, and more particularly to devices for controlling the flow of fuel in carburetors.

An object of the invention is to provide an improved means for controlling the flow of fuel to the nozzle of the carburetor at starting, upon acceleration, at low speeds, and at high speeds.

A further object of the invention is to combine an acceleration pump and an economizer in a single simplified unit, thereby facilitating the construction and assembly of the carburetor.

A further object of the invention is to provide common means for controlling the operation of the acceleration pump and economizer.

15 A further object of the invention is to provide an improved economizer controlled by the position of the throttle.

Further objects and advantages of the invention will be apparent from the following description, taken in connection with the appended drawing, in which:

20 Figure 1 is a side elevation of a carburetor embodying the invention, parts being broken away to disclose the construction.

25 Figure 2 is an enlarged sectional view of the combined acceleration pump and economizer; and

Figure 3 is an enlarged sectional view taken on the line 3—3 of Figure 2.

30 The invention is illustrated as applied to a down draft plain tube carburetor, but it will be understood that it may be applied to other types as well. The carburetor illustrated comprises a body portion 10 forming a vertical passageway for air and fuel, controlled by a choke valve 12 and a throttle valve 14 and supplied with fuel by means of a main nozzle 16. The carburetor also comprises a float chamber 18 of any suitable construction, and within the float chamber is mounted a combined acceleration pump 35 and economizer 20 constructed in accordance with this invention.

40 The device 20 comprises a movable cylinder or cup 22 closed at its upper end by a head 24, which head is connected to an operating rod 26, this rod being pivoted at 28 to a lever 30 which is pivoted at 29 to the body of the carburetor and urged upwardly by a leaf spring 32. A rod 34 is connected at its upper end to lever 30 at 31 and at its lower end to a crank arm 36 which is fixed to the shaft of throttle 14. The mechanism thus far described is disclosed and claimed in the application of Don Cole, Serial No. 290,393, filed July 5, 1928.

45 50 55 55 The connection 31 is preferably formed by

passing the upper end of rod 34 through a hole in lever 30 and securing nuts 38 thereto, so that when the throttle is opened the lever 30 is forced downwardly, thereby causing the cup 22 to be depressed, but when the throttle is closed the lever 30 need not move upwardly since there is no positive connection for upward movement of the lever. The spring 32 urges lever 30 upwardly at all times, thereby tending to close the throttle valve 14.

60 65 The cup 22 is provided with a movable piston 40 which has a relatively loose fit therein and is urged upwardly by a compression spring 41. The piston is provided with a conical valve seat 42 at its upper end, and has a central bore which 70 slidably engages a stem 43 fixed to the base of the float chamber. The stem 43 has a conical head adapted to cooperate with valve seat 42 and provided with radial passageways 44 communicating with an axial bore 46 which in turn 75 communicates through ducts 48 with a passageway 50 leading to the main nozzle 16.

80 85 90 The lower portion of stem 43 is provided with a central bore 52 within which is threaded a member 54 which extends upwardly within the bore 46 and closes the upper end thereof. The upper end of member 54 is cup-shaped, its outer surface being spaced from the inner wall of stem 43 to permit fuel to pass therebetween, and its inner surface is adapted to receive a coiled compression spring 56 which acts upon a valve stem 58 slidably mounted within a bore in the member 54. The lower end of valve stem 58 is provided with a conical portion 60 terminating in a disk 62, a cooperating valve seat being formed 95 in bore 52. The member 60 thus controls the communication of bore 52 with a passageway 64 leading through a metering orifice 66 to passageway 50 and thence to the main nozzle.

9 9 9 Radial passageways 68 (Figure 3) lead from bore 52 to the exterior of stem 53, thus communicating with the float chamber below the level of fuel therein.

1 1 1 It can now be seen that if the throttle is opened cup 22 is depressed, and any liquid which is contained within the cup will transmit pressure to the upper end of the piston 40 and force the same downwardly against the force of spring 41, thereby opening the valve ports 44 and permitting the discharge of liquid therethrough and through the ducts 48 and passageway 50 to the nozzle 16.

1 1 1 If the cup 22 is held down, the spring 41 gradually moves the piston 40 upwardly, expelling fuel until the valve seat 42 closes the ports 44 and thus

both limits the upward travel of the piston 40 and closes off communication between the interior of the cup 22 and the nozzle 16. In effect the piston forms an overrunning valve for 5 the ports 44.

Upon upward motion of the throttle toward closed position the spring 32 tends to raise the lever 30 and thus causes a drop of pressure inside the cup 22, and liquid flows into the cup 10 through the clearance between the piston and the cup.

It will be observed that the upper end of cup 22 extends above the liquid level in the float chamber, and the cylinder in operation may become filled with liquid up to or above said level. 15 The stem 26 passes loosely through a hole in the float chamber cover, to permit pivot 28 to follow its arcuate path.

A carburetor constructed as aforesaid tends to 20 give a mixture which becomes too lean at wide open throttle, and the economizer above described is accordingly provided to open the auxiliary passageways 68 for fuel between the float chamber 18 and the nozzle 16 when the throttle 25 valve approaches its wide open position. The economizer is brought into operation when the inner surface of head 24 contacts with the upper end of valve stem 58 and moves it downwardly against the force of spring 56. This permits fuel 30 to flow from the float chamber through radial passageways 68, bore 52, passageway 64, metering orifice 66, and passageway 50 to the main nozzle.

While the invention has been described with particular reference to a specific embodiment 35 thereof, it is not our intention to limit it to such embodiment, or otherwise except in accordance with the appended claims.

We claim:

1. Fuel supply means for a carburetor having 40 a fuel reservoir and a fuel nozzle, comprising a member extending into the fuel reservoir and having a bore communicating with the nozzle, a fuel container reciprocable thereon, a yielding piston between said member and said container, 45 a conduit in said member communicating with the reservoir and the nozzle, a valve in the conduit, and means operative upon movement of the fuel container to a predetermined position to open said valve.

50 2. Fuel supply means for a carburetor having a fuel reservoir and a fuel nozzle, comprising a

stationary member extending into the reservoir, a fuel container reciprocable on said member, a bore in said member communicating with said container and said nozzle, a second bore in said member communicating with said reservoir and said nozzle but not with said container, a valve controlling said second bore, and means operative upon movement of the container to a predetermined position to open said valve. 80

3. Fuel supply means for a carburetor having a fuel reservoir and a fuel nozzle, comprising a member extending into the reservoir, a bore in said member communicating with the fuel nozzle, a second member movable with respect to the first mentioned member to form a pump chamber and force fuel through said bore, a second bore in said first mentioned member communicating with said reservoir and said nozzle but not with said pump chamber, and a valve controlling the second bore and adapted to be opened by relative movement between said first mentioned member and said second member. 85

4. Fuel supply means for a carburetor having a fuel nozzle, comprising a fuel reservoir, a member in said reservoir, a bore in said member communicating with said fuel nozzle, a second member in the reservoir movable with respect to the first mentioned member to form a pump chamber and force fuel through said bore, a second bore in said first mentioned member communicating with said reservoir and with said fuel nozzle but not with said pump chamber, a metering restriction in said second bore, and control means for the second bore operative in accordance with the relative positions of said first mentioned member and said second member. 90

5. Fuel supply means for a carburetor having a fuel reservoir and a mixing chamber, comprising a fixed stem in said reservoir having an aperture communicating with the mixing chamber, a cylinder reciprocable on the stem to force fuel through said bore, a yielding piston interposed between the stem and cylinder and controlling the flow of fuel through said bore, a second bore in said stem communicating directly with the 115 reservoir and communicating with the mixing chamber, and a valve yieldingly mounted in said stem and having a valve stem projecting into the path of the cylinder to be actuated thereby. 110
